CLAIM

The ornamental design for a light switch extension, as shown and described.

DESCRIPTION

FIG. 1 is an exploded perspective view of the light switch extension showing my new design;

FIG. 2 is a front elevational view thereof;

FIG. 3 is a rear elevational view thereof;

FIG. 4 is a left side elevational view thereof, the right side elevational view being a mirror image of the view shown in the Figure;

FIG. 5 is a top plan view thereof; and,

FIG. 6 is a bottom plan view thereof.
